NEAR RECEIVER HAVING REED DETECTOR AND HAVING FLUID DIAPHRAGM TIME DELAY CONTROL OF ALARM
Robert H. Voigt, Milford, Mich., assignor to Aseco, Incorporated, Milford, Mich., a corporation of Michigan
Filed Jan. 29, 1962, Ser. No. 169,463
9 Claims. (Cl. 340—310)

This invention relates to electrical control circuits for producing a delayed action and controlled duration audible alarm and more particularly to a receiving instrument preferably designed to be used in homes, offices and other buildings as a component of the National Emergency Alarm Repeater (NEAR) system.

The task of providing a means of alerting the nation in the event of an enemy attack has been given by Congress to the Office of Civil and Defense Mobilization. This organization has long recognized that some means had to be found to supplement outdoor sirens in providing more effective warning since sirens often can not be heard indoors, and many suburban and rural areas are not within the range of hearing of the nearest municipal siren system. After considerable investigation and research it has been finally decided that what is needed is an indoor system which can be coordinated with the outdoor sirens already installed.

Since such a system must reach the greatest number of homes and buildings and still not entail undue costs, it has been decided to make use of existing electric power lines. Generating equipment will transmit a signal in the form of a short burst of 270 cycles per second frequency superimposed on the 60 cycle power normally being transmitted through the power lines. A receiver unit which is plugged into an ordinary wall receptacle will actuate a buzzer or bell upon receipt of the signal.

Certain safeguards must be built into the receiving component for this system to prevent false alarms. Means must be provided for delaying the sounding of the alarm for 10 to 15 seconds so that brief surges of power which could be caused by lightning bolts, man made switching transients and coded signals will not actuate the alarm. The timing means utilized must not be cumulative to short pulses since several lightning bolts or coded signals of 2 to 5 seconds' duration each might accumulate to produce a false alarm. The NEAR receiver must select a frequency of 270 cycles plus or minus one cycle and reject all other frequencies. It must also reject a voltage amplitude of .5 volt R.M.S. or less. Additionally, the receiver must be inexpensive, probably less than \$10.00.

It is an object then of the present invention to produce a reliable signal receiving and alerting unit by providing a time delay switching mechanism which provides a fixed time delay before setting off an audible alarm and which operates independently of power line voltage, ambient temperature or relative humidity.

It is another object of the present invention to produce a receiving and alerting device for the NEAR system which will not be actuated by lightning bolts, switching transients or coded signals by providing a time delay switching mechanism which will respond only to a minimum signal duration of 10 to 15 seconds.

It is still another object of the present invention to provide a NEAR receiving component which will not be cumulative to short pulses of actuating frequency by providing a time delay switching mechanism which will reset almost immediately after it is de-energized.

Yet another object of the present invention is to reduce manufacturing costs of a NEAR receiving and alerting

2

component by providing a simply constructed time delay switching mechanism.

Still another object of the present invention is to insure the audibility of the alarm actuated by the receiving component by providing a second time delay switch mechanism which independently controls the duration of the audible alarm after the requisite signal pulse has been received.

A further object of the present invention is to produce a more reliable NEAR receiving component by providing a frequency selective circuit which will admit only a frequency of 270 cycles per second plus or minus one cycle and by providing a voltage amplitude selective circuit which will reject signals with a voltage level of less than .5 volt R.M.S.

Other objects and advantages of the present invention will be readily apparent upon reference to the following drawings in which like reference characters refer to like parts throughout the several views and in which

FIG. 1 is a diagrammatic view of a preferred embodiment of the present invention.

FIG. 2 is a diagrammatic view of another preferred embodiment of the present invention.

FIG. 3 is a perspective view of a preferred embodiment with portions removed for purposes of clarity.

FIG. 4 is a perspective view of the components of the preferred device adapted for connection within the preferred embodiment shown in FIG. 3.

FIG. 5 is an elevational view of a fluid cell of the present invention.

FIG. 6 is a cross sectional view taken substantially at line 6—6 of FIG. 5, and

FIG. 7 is a view substantially like FIG. 6 but illustrating another preferred fluid cell adaptable to the present invention.

Now referring to the drawings for a more complete understanding of the present invention, FIG. 1 illustrates diagrammatically a preferred receiving unit as comprising an input line plug 1 adapted for insertion into an ordinary A.C. current household wall receptacle (not shown) and having prongs 2 and 3. The prong 2 is connected to a rectifier 4 of any desired type which rectifies the A.C. current (preferably 110 volt 60 cycle current) to a pulsating D.C. current.

A neon lamp circuit indicated generally at 5 and a resonance circuit indicated at 6 are each connected across the plug 1 as shown. The neon lamp circuit 5 preferably comprises voltage divider resistors 7 and 8 with a neon lamp 9 connected as shown. A small amount of energy thus flows through the neon lamp circuit 5 energizing the neon lamp 9, indicating that the receiver is connected into the supply line and that the voltage is at a sufficient level for receiver operation.

A small amount of energy normally passes through the resonance circuit 6 which preferably includes a capacitor 10 and an electromagnetic coil 11 which form a series tuned LC circuit. The capacitive reactance of the capacitor 10 would be approximately the same as the inductive reactance of the electromagnetic coil 11 at the predetermined signal frequency, thus the reactances cancel one another and the circuit is resonant at that frequency. The present frequency for the NEAR system is 240 cycles, but this frequency may be changed at some future date.

A resonance relay means 12 is disposed within the magnetic field of the electromagnetic coil 11 and preferably comprises a normally open switch 14 having one contact 14A fixed to a resonance reed 15 which is mounted at one end at 15A, with the other contact 14B being connected to the D.C. side of the rectifier 4.

The resonance reed 15 is connected to an isolation relay circuit, as indicated generally at 16, comprising a

resistor 17 and a connected capacitor 18 which cooperate to form an RC filter network. An electromagnetic coil 20 is connected at one end to a point in the filter circuit intermediate the resistor 17 and the capacitor 18, and at the other end with the prong side of the plug 1. The capacitor 18 is also connected with the prong 3 side of the plug 1. A normally open switch 22 is disposed closely adjacent the electromagnetic coil 20 and has a contact 23 operated thereby. The filter network as above described operates to partially filter out the D.C. pulsations from the rectifier 4 when the resonant relay circuit is actuated, so that the switch 22 will remain closed. The switch 23 is connected with the D.C. side of the rectifier 4 while the other switch contact 24 is connected with an electromagnetic coil 26.

An armature 27 is disposed closely adjacent the electromagnetic coil 26 and is operably connected to an axially movable pin 28. The pin 28 is preferably spring loaded in the direction of the arrow to hold the diaphragm 29A of a time delay fluid cell 29 in a normally closed or exhausted position, the diaphragm 29A preferably being carried in a retaining cup 29B.

A normally open switch 31 is disposed between the fluid cell 29 and the armature 27 and comprises normally spaced contact members 32, 33 and 34 each carried on the end of spring leaf members 35, 36 and 37 respectively. The leaf 15 carrying the contact 32 is connected as shown with the D.C. side of the rectifier 4. The leaf 36 carrying the contact 33 is connected with the prong 3 side of the plug 1 through an electromagnetic coil 38. A clapper 39 is pivotally disposed near the coil 38. The leaf member 37 is of a bi-metal construction, the two metals having different thermal characteristics and arranged such that heating will tend to warp it toward the dotted line position shown. A thermal heater winding 40 is connected in parallel with the coil 38 and is disposed closely adjacent the leaf 37 as shown.

In operation, a small portion of the 110 volt 60 cycle current normally flows through the neon lamp circuit 5. This flow energizes the lamp 9 indicating the receiver is connected to a source of power of adequate amplitude. A small amount of energy also flows through the resonance circuit 6 without energizing the electromagnetic coil 11 sufficiently to initiate a response in the resonance reed 15.

When a signal of 270 cycles plus or minus one cycle of sufficient amplitude is present across the plug 1, it passes through the resonance circuit 6, causing the resonant reed 15 to vibrate at its natural frequency of 270 cycles per second. The reed 15 will swing in an arc sufficient to cause the switch 14 to open and close 270 times each second. This will act to introduce a current flow from the D.C. rectifier 4, through the isolation relay 16. With the filter network partially filtering out the D.C. pulsations, the electromagnetic coil 20 is energized and will draw the contact 23 against the contact 24, thus closing the circuit to energize the electromagnet 26 which in turn attracts the armature 27. The pin 28 is thus moved away from the fluid cell 29, thus releasing the holding force against the diaphragm 29A. The surrounding fluid (normally air) acts to slowly expand the diaphragm 29A, as will be explained more fully below, causing the contact 32 to engage the contact 33 and finally the contact 33 to engage 34. This is the means by which the required time delay from the receipt of the signal is produced. Preferably this time delay will be about 15 seconds.

As contacts 32, 33 and 34 engage, the heater winding 49 and the electromagnet 38 will be energized. The clapper 39 will be vibrated to strike the side of the housing 41 of the receiver or other adjacent structure producing an audible alarm.

The alarm actuation signal of 270 cycles will normally be released after 20 seconds, but it is necessary to provide means for continuing the alarm for a period of 40

5 to 60 seconds. As long as the contacts 32-33-34 are engaged, the alarm will continue, and it will be seen that the contacts 32 and 34 when closed, operate as a holding circuit, to energize the electromagnet 26 independently of the resonant relay circuit which opens on cessation of the 20 second actuation signal.

The bimetal leaf 37 will gradually be heated by the heater winding 40 until the leaf 37 warps away from contact 33 thus breaking the circuit, deenergizing the coil 26 so that the pin 28 will immediately collapse the diaphragm 29A. This opens the switch contacts 32 and 33, breaking the alarm and heating circuits.

10 FIG. 2 illustrates a modification of the present invention in which a plug 102 is connected to a D.C. rectifier 104. A normally open switch 114 having one contact 114A carried adjacent a resonant reed 115 and the other contact 114B carried on a leaf 114C pivotally mounted on a hair spring 114D.

15 The contact 114 is connected with the D.C. side of the rectifier 104. The leaf 114C is connected with an electromagnetic coil 126 and a contact 134 positioned at the end of a bimetal leaf 137. An armature 127 is positioned closely adjacent the electromagnetic coil 126 and carries an axially movable pin 128. The pin 128 is positioned to hold a fluid cell diaphragm 129 in a normally closed or exhausted position. Contacts 132 and 133 are each carried at the end of leaf members 135 and 136 respectively. The leaf 135 is connected to the D.C. side of the rectifier 104 and the leaf 136 is connected to a heater winding 140 and a coil 111 in a resonance circuit 106.

20 The plug 102 is also connected to the resonance circuit 106 as shown, comprising a capacitor 110 and the electromagnetic coil 111. A neon lamp circuit 105 comprising a lamp 109 and a pair of divided resistors 107 and 108 also is connected across the plug 102 as shown. A clapper 139 is positioned closely adjacent the coil 111.

25 The embodiment illustrated in FIG. 2 operates as follows: The alarm actuating signal passes through the resonance reed 115 to vibrate causing the switch 114 to close. The hair spring 114D will be induced to vibrate the leaf 114C as the reed 115 vibrates thus producing non-interrupting contact through the switch 114. This energizes the electromagnet 126 causing the armature 127 and the pin 128 to move, setting into operation the slow expansion of the fluid cell diaphragm 129. As the contacts 132-133-134 engage the armature 127 is held in position, the heater winding 140 is energized and a flow of current to the electromagnetic coil 111 is maintained even after the actuating signal ceases. The coil 111 excites the clapper 139 and an audible alarm is sounded. The alarm continues until the heater winding 140 heats the bimetal leaf 137 sufficiently to cause it to warp, opening the contacts 133 and 134 to break the current flow through the coil 126. The pin 128 thus collapses the diaphragm 129 to separate the contacts 133 and 132 breaking current flow to the coil 111 and the heater coil 140.

30 FIGS. 3 and 4 are views illustrating a preferred assembly of a NEAR receiver embodying the present invention. The box-like outer housing 41 carries the clapper 39 and the electromagnet 38. The other elements are carried on a flat closure plate member 42 shown in FIG. 4. In assembling the receiver, the housing 41 is positioned over the elements carried on the bottom member 42 and screws (not shown) are inserted through the aligning holes 43 and 44 provided in the housing 41 and the bottom member 42 respectively.

35 FIGS. 5 and 6 illustrate the construction of the preferred fluid cell 29 of the present invention. The fluid cell 29 comprises a diaphragm 29A and the retaining cup 29B. A spring 46 is seated in the retaining cup 29B and urges the diaphragm 29A outwardly. A retaining ring 46 cooperates with radially inwardly bent portions 47 of the retaining cup 29B to seat the diaphragm 29A

in the retaining cup 29B. The retaining ring 46 is provided with an inwardly spaced linear edge portion 48. The diaphragm 29A is provided with a perforation 49 which carries a wick 50 extending inwardly into the diaphragm 29A. The fluid cell 29 is normally in a deflated position held thus by the pin 28 or 128 of FIGS. 1 and 2, the spring 45 being under compression. In being urged to this position, the linear edge portion 48 of the retaining ring 46 permits a portion of the edge lip of the diaphragm 29A to move away from the retaining cup 29B as shown in the dotted line position of FIG. 6, in the nature of a check valve, to permit the fluid in the interior of the diaphragm to exhaust. As the axial pin 28 moves away from the diaphragm 29A, fluid is permitted to enter the diaphragm 29A through the perforation 49, the wick 50 providing the means by which entry of the fluid and thus the expansion of the diaphragm 29A is delayed. The closeness of weave of the wick 50 will determine how fast fluid enters and thus will regulate the delay interval.

FIG. 7 shows another preferred fluid cell 229 comprising a diaphragm 229A, a retaining cup 229B, a spring 245 and a retaining ring 246. A passage 250 communicates the space between the diaphragm 229A and retaining cup 229B with the interior bellows 251. A needle valve assembly 252 adjustably regulates the flow of fluid through a bypass passage 253. A spring biased ball 254 acts as a check valve permitting fluid to flow substantially freely from the passage 250 to the bellows 151 but preventing reverse flow of the fluid. As the axial pin 28 moves to deflate the diaphragm 229A fluid moves through the passage 250 to the bellows 251 opening the check valve ball 254. As the pin 28 moves away from the diaphragm 229A, the ball 254 prevents fluid from entering the passage 250 without passing through the bypass passage 253. The needle valve 252 can be adjusted to regulate the flow of fluid through the bypass passage 253 and thus regulate the time required by the diaphragm 229A to expand.

In both modifications of the invention above described, it will be seen that no accumulations of short duration actuation signals will operate to set off a false alarm, since when the resonance circuit is broken prior to closing of the holding circuit, the armature pin will immediately collapse the diaphragm and this resets the device to its normal position.

The components of the receiver are also inexpensive and the circuitry is not very complex, lending itself well to printed circuitry manufacture, enabling costs to be held well below the figure which will make the NEAR system readily available nationwide.

The system described accurately responds to the required close tolerance frequency and amplitude range, rejecting all others, and incorporates the necessary delay feature without undue complexity which might otherwise result in failures and/or false alarms.

Although I have described but two embodiments of the present invention, it will be apparent to one skilled in the art that other changes and modifications could be made without departing from the spirit of the invention or the scope of the appended claims.

I claim:

1. In an alarm circuit having a source of electrical power and means selectively imposing a predetermined actuation signal thereon, a delayed actuation device comprising

- (a) an alarm circuit including a switch and means producing an audible alarm upon actuation of said switch,
- (b) means actuating said switch and including an energizing circuit and a time delay means,
- (c) said energizing circuit being operable to actuate said time delay means upon receipt of said predetermined actuation signal,
- (d) said time delay means being operable to actuate

said switch upon the lapse of a predetermined time interval after the actuation by said energizing circuit,

- (e) said time delay means comprising a fluid cell diaphragm being operable to urge said switch toward its actuated position as said diaphragm expands, means normally holding said diaphragm in a collapsed condition, and said holding means being actuated by said energizing circuit to release said diaphragm to expand whereby said switch is slowly urged toward a closed condition,
- (f) a second time delay means operable to retain said holding means in a released position for a predetermined time interval after cessation of said predetermined actuation signal, and
- (g) said switch comprising a pair of closely adjacent contact members, and
- (h) said second delay means comprising heating means provided on one of said contact members, means energizing said heating means upon said diaphragm being expanded a predetermined degree, and said other contact member having heat responsive means operable to separate said contacts upon being heated a predetermined amount by said heating means whereby said switch is opened after a predetermined time interval.

2. In an alarm system having a source of electrical power and means selectively imposing a predetermined actuation signal thereon, a delayed action alarm device comprising,

- (a) an alarm circuit including a switch and means producing an audible alarm upon the actuation of said switch,
- (b) a resonance circuit including a capacitor tuned to the frequency of said actuation signal and an electromagnetic coil,
- (c) a resonance relay having a switch disposed closely adjacent said electromagnetic coil and being actuated upon receipt of said actuation signal by said capacitor,
- (d) a time delay means being energized by the actuation of said relay switch,
- (e) said time delay means being operable to actuate said alarm circuit switch after the lapse of a predetermined period,
- (f) holding means being operable to hold said alarm circuit switch in its actuated position for a predetermined time interval,
- (g) said time delay means comprising a fluid cell diaphragm being operable to urge said alarm switch toward an actuated position as said diaphragm expands and means normally holding said diaphragm in a collapsed condition,
- (h) said holding means being energized through said resonance relay to permit said diaphragm to expand,
- (i) means urging said diaphragm toward said expanded condition,
- (j) said diaphragm being provided with means permitting fluid to slowly enter said diaphragm.

3. The system as defined in claim 2 and in which said holding means comprises,

- (a) an axially movable pin and means normally urging said pin toward said diaphragm to urge same toward a collapsed condition,
- (b) an armature operably connected to said pin, and
- (c) an electromagnetic coil disposed closely adjacent said armature and operable upon being energized to urge said armature toward said coil whereby said pin is axially moved away from said diaphragm.

4. In an alarm system having a source of electrical power and means selectively imposing a predetermined actuation signal thereon.

- (a) a switch and a fluid cell actuator therefor,
- (b) said fluid cell actuator comprising a casing having a fluid chamber, a diaphragm closing one side of said chamber, and spring means resiliently urging

- said diaphragm toward an expanded position to activate said switch,
- (c) means normally collapsing said diaphragm against the force of said spring means to reduce the volume of said chamber,
- (d) electromagnet means energized on receipt of said predetermined actuation signal and operable when energized to remove said collapsing means from said diaphragm and allow same to be urged toward the expanded position
- (e) means slowly admitting fluid to said chamber, and
- (f) alarm means operated upon actuation of said switch following delayed expansion of said diaphragm.

5. The system as defined in claim 4 and including means operable to actuate said collapsing means to return said diaphragm to said first position upon said predetermined actuation signal ceasing prior to actuation of said switch.

6. The device as defined in claim 5 and including holding means actuated upon actuation of said switch and 20 operable upon being actuated to hold said switch in its actuated position for a predetermined time interval.

7. The system as defined in claim 4 and in which said fluid cell actuator further comprises,

(a) a retaining cup and said diaphragm member being 25 secured to said cup to define said closed chamber,

(b) said spring means being carried by said cup and

10

urging said diaphragm member outwardly with respect to said cup to urge said fluid cell actuator towards said expanded position.

8. The device as defined in claim 4 and in which said fluid admitting means comprises a wick member disposed with one end in said chamber and the other end exteriorly of said fluid cell actuator.

9. The device as defined in claim 4 and including valve means provided in said fluid cell actuator operable to open communication between said chamber and the exterior of said fluid cell actuator only upon movement of said fluid cell actuator from said expanded position towards said collapsed position.
